UNITED STATES PATENT OFFICE.

CHESTER McNEIL, OF CHICAGO, ILLINOIS, ASSIGNOR TO UNION SPECIAL MACHINE COMPANY, OF CHICAGO, ILLINOIS, A CORPORATION OF ILLINOIS.

SEAM FOR SEWED ARTICLES.

1,214,563.

Specification of Letters Patent.

Patented Feb. 6, 1917.

Application filed March 5, 1915. Serial No. 12,347.

To all whom it may concern:

Be it known that I, CHESTER McNEIL, a citizen of the United States, residing at Chicago, in the county of Cook, State of Illinois, have invented certain new and useful Improvements in Seams for Sewed Articles, of which the following is a description, reference being had to the accompanying drawing and to the figures of reference marked thereon.

This invention relates to new and useful improvements in seams for sewed articles, and more particularly to a flat seam for uniting two abutting edges of fabrics.

An object of the invention is to provide a flat seam for uniting the abutting edges of two pieces of fabric, which is formed of four parallel rows of needle loops passed down through the fabrics, the two outer rows being considerably within the edges of the respective pieces of fabric, and the two inner rows being a short distance within the edges thereof. A single cross thread on one side of the fabric concatenates with all the needle loops, and is formed into loops which extend longitudinally of the seam, the strands of which pass through and embrace said needle loops, thus covering the under face of the fabric.

On the upper face of the fabric two cross threads are laid back and forth from one outer line of loops to the other outer line of loops, each thread embracing alternate needle loops in each row and being bound down to the fabric by all four of the needle threads between the respective loops thereof.

In the drawings, Figure 1 is a top plan view of a seam for uniting abutted edges, which seam embodies my invention; Fig. 2 is a bottom plan thereof; and Fig. 3 is a cross section of the seam.

In these drawings, 1 and 2 represent two trimmed and abutted edges of fabric, which are brought together along the line 3. 4, 5, 6 and 7 represent four parallel needle threads having respectively formed therein needle loops 8, 9, 10 and 11 passed down through the fabric, two (8 and 11) considerably within the edge of the respective portions of fabric, and the others (9 and 10) considerably nearer the edges of the respective portions.

The loops are concatenated on the under face of the fabrics with a single looper thread 12, a strand of which 13 passes

through all the needle loops, is then looped around a succeeding outer needle loop 11, then passes through the first needle loop 11, then around an intermediate succeeding needle loop 10, then through the preceding intermediate needle loop 10, then around the succeeding needle loop 9 in the other intermediate row, then through the preceding loop 9 in the said latter intermediate row, then around the succeeding loop 8 in the other outer row of loops; then through the preceding loop 8 in said outer row, and then as at 13 through all four of said succeeding loops.

Referring to Fig. 1, 14 is a cross thread passing alternately from outside lines of loops (8 or 11) to the other outside line of loops (11 or 8). It passes under the needle threads of all four lines between the loops therein, as well as around every other loop of the two outside lines 8 and 11 at the point where said loop emerges from the fabric. Another cross thread 15 passes back and fourth across the fabric, but in an opposite direction, and is similarly held to the portions thereof and cross each other at the line 3 of the abutting portions of the fabric.

It will be seen that by my improved seam the two outer rows of loops with their concatenated under thread and the interwoven cross threads on the upper surface, form anchoring stitches which resist transverse strain while the intermediate rows of loops with their cross threads serve not only to unite but to bind down the raw edges or "whiskers" on the edges of the fabric portions. Furthermore, the course which the lower thread takes in its interweaving with the loops of the needle thread serves to fully cover the edges of the fabric and bind down the threads and the loose ends of the fabric, while on the upper surface the cross threads between the outer rows of loops serve not only to cover the surface, but to anchor the outside rows.

It will be understood that this seam may be used for ornamenting the flat face of a fabric or for an ornamental border.

Having thus described my invention, what I claim as new and desire to secure by Letters Patent, is:—

1. In a seam, the combination with two opposing edges of fabric, four parallel rows of needle loops passing through the fabric, 110

two within each edge, a single cross thread connecting all the loops on one face of the fabric, and a cross thread connecting the threads on the other face of the fabric and 5 bound down by said threads between the consecutive loops thereof.

2. In a seam, the combination with two opposing edges of fabric, four parallel rows of needle loops passing through the fabrics, 10 two within each edge, and a single cross thread connecting all the loops on one face of the fabric, and two cross threads connecting the threads on the other face of the fabric and bound down by said threads between 15 the consecutive loops thereof.

3. In a seam, the combination with a fabric, of four parallel rows of needle loops passing through the fabric, and a single cross thread having a strand passing directly 20 through all four of said loops transversely of the seam and having diagonal strands extending longitudinally of the line of seam and alternately encircling and passing through succeeding and preceding needle loops, and cross threads on the upper face of 25 the fabric passing alternately back and forth between the outer rows of loops crossing each other at the center and bound down by the needle threads between the loops.

the fabric passing alternately back and forth between the outer rows of loops, crossing each other at the center and bound down by the needle threads between the loops.

4. In a seam, the combination with two 30 opposing edges of fabric, four parallel rows of needle loops passing through the fabrics two within each edge, and a single cross thread having a strand passing directly 35 through all four of said loops transversely of the seam and having diagonal strands extending longitudinally of the line of seam and alternately encircling and passing through succeeding and preceding needle loops, and cross threads on the upper face of 40 the fabric passing alternately back and forth between the outer rows of loops crossing each other at the center and bound down by the needle threads between the loops.

In testimony whereof, I affix my signature, 45 in the presence of two witnesses.

CHESTER McNEIL.
